DEWAXING APPARATUS

William Blewett Chenault, Wellsville, N. Y., assignor to Sinclair Refining Company, New York, N. Y., a corporation of Maine

Application December 3, 1937, Serial No. 177,870

2 Claims. (Cl. 233—1)

This invention relates to apparatus for use in dewaxing hydrocarbon oils and, more particularly, to apparatus for use in the centrifugal dewaxing of hydrocarbon oils. In its more specific aspect, my invention relates to a sight-glass for use in conjunction with centrifugal dewaxing machines whereby a sample of dewaxed oil discharged from said machines may be drawn off, inspected while stationary, and then returned to the main body of dewaxed oil.

The centrifugal dewaxing machines in general use today for the continuous dewaxing of hydrocarbon oils are provided with a rundown line through which the substantially wax free oil dissolved in a suitable diluent is discharged from the centrifuge. This rundown line is further provided with a look-box which comprises an enlarged portion of the line having a glass face so that an operator may observe the flow of wax free oil through the rundown line. Due to the fact that the wax free oil is discharged from the centrifuge at a low temperature, the look-box soon frosts over to such an extent that it is difficult to see the oil flowing through the rundown line. Moreover, it is necessary that the wax free oil be unhindered in its flow through the rundown line, and for this reason the oil flowing through the look-box is in continual motion.

In order to observe the physical condition of the wax free oil discharged from the centrifuge it has become the general practice to take a sample of the wax free oil and examine the sample to ascertain whether or not the discharged oil contains particles of suspended wax. Heretofore these samples of the wax free oil have been obtained, for example, by removing a plug from a hole in the rundown line, inserting into this hole in the rundown line a nipple with a cut-away section, and withdrawing a sample of the wax free oil into an improvised look-box having glass sides mounted in a wooden frame. This method of taking a sample of the oil has been characterized by a considerable amount of spillage on the floor around the centrifuge. When naphtha or other similarly highly inflammable diluent is used as the dewaxing agent in the centrifuge, this spillage has presented a serious fire hazard. Furthermore, it has been necessary heretofore to remove from the rundown line at least about five or six times the volume of the improvised look-glass in order that the sample finally obtained be substantially at the temperature of the oil as it is discharged from the centrifuge. Inasmuch as this wax free oil withdrawn for sampling must be discarded, a substantial waste has been the natu-

ral concomitant of the sampling operation. When it is considered that samples must be withdrawn at frequent intervals from as many as forty or more machines in a single plant, the extent of this waste will be readily apparent. Moreover, due to the length of time required to obtain and to inspect this sample, serious difficulty has been encountered due to the increase in temperature of the sample of oil. Any wax which may have been crystallized and which may have been visible in the oil as it leaves the centrifuge dissolves in the diluent with the rise in temperature thereof. Still another difficulty has been encountered in obtaining such a sample of wax free oil in that air and moisture drawn into the sample from the atmosphere give a cloudy appearance to the sample with resulting difficulty in obtaining a satisfactory inspection of the sample.

I have discovered that a truly representative sample of the wax free oil may be obtained, that spillage may be avoided, and that the waste of large volumes of oil heretofore necessarily removed from the rundown line and subsequently discarded can be eliminated by means of a sight-glass installed in the rundown line of the centrifugal machine. This sight-glass comprises means for withdrawing at least a portion of the substantially wax free oil from the rundown line of the centrifugal machine, means for visibly confining the oil withdrawn from the rundown line, and means for returning said portion of oil to the rundown line. Additional means are provided with advantage for bringing this portion of oil to rest within the transparent tube whereby a satisfactory inspection of the portion of oil may be made while the oil is stationary.

The apparatus of my invention will be more fully understood by a consideration of the accompanying drawing in which:

Figure 1 comprises a perspective view of a portion of a typical centrifugal machine showing the rundown line with the sight-glass of my invention;

Figure 2 is an enlarged view of the sight-glass of my invention showing its installation in the rundown line; and

Figure 3 is a sectional view taken along line 3—3 of Figure 2 showing the details of the upper connection for the sight-glass with the rundown line.

As shown in Figures 1 and 2, the sight-glass of my invention comprises a glass tube 5 suitably connected by means of a packing gland 6 with a nipple 7. A portion of one end 8 of this nipple is cut away as shown in Figures 2 and 3 and is

preferably threaded into the rundown line so as to maintain a sealed connection. The cutaway portion of the nipple inserted into the rundown line with the cutaway portion facing upwardly 5 acts as a trough to carry off at least a portion of the wax free oil flowing through the rundown line. The lower end of the glass tube is connected by means of a packing gland 10 with a suitable valve 11 which, in turn, is connected to 10 pipe 12 communicating with the rundown line. This pipe is suitably connected with the rundown line by means of a bushing 13, or the like, at a point in the rundown line preferably below the look-box 14. Thus, it will be seen that the sight 15 glass of my invention comprises a transparent tube suitably connected at either end to different points in the rundown line of the centrifugal machine whereby at least a portion of the substantially wax free oil flowing through the rundown 20 line may be withdrawn from the line, inspected while stationary, and then returned to the line.

In using the sight-glass of my invention to inspect a sample of oil the valve 11 is opened and the oil caught in the cutaway portion 8 of 25 nipple 7 runs through glass tube 5, through valve 11 and pipe 12 back into the rundown line. After the oil has run through the sight-glass for a sufficient length of time so that the temperature of the oil in the sight-glass is sub- 30 stantially that of the oil as it is discharged from the centrifuge into the rundown line, valve 11 is closed and the oil in the sight-glass brought to rest. Any frost which may have formed on the outside of the glass tube made be easily re- 35 moved by wiping it with a cloth moistened with alcohol, or some equivalent means. In this way, the operator may readily inspect the oil to determine whether or not the oil contains suspended particles of wax which, if present in 40 the oil, should be removed by subsequent treatment thereof.

It will be seen, therefore, that the sight-glass of my invention comprises an inexpensive device which may be readily attached to the rundown line of a centrifugal machine. Inasmuch 45

as this sight-glass is connected at all times in a closed circuit with the rundown line, there is avoided the fire hazard encountered heretofore by the spillage of oil and solvent around the machine. Furthermore, the temperature of the oil in the sight-glass is substantially that of the oil as it leaves the centrifuge and comprises a truly representative sample of the substantially wax free oil. Inasmuch as the oil which passes through the sight-glass is returned to the rundown line, there is eliminated the substantial waste which heretofore has been characteristic of the sampling operation.

I claim:

1. In a centrifugal machine for removing precipitated wax from hydrocarbon oils, the centrifugal machine being provided with a rundown line for discharging substantially wax free oil from the machine, the improvement which comprises means extending within the rundown line 15 for withdrawing at least a portion of the oil from the rundown line, a transparent tube for visibly confining the oil withdrawn from the rundown line, means for returning said portion of oil to the rundown line, and means disposed intermediate 20 the transparent tube and said returning means for bringing said portion of oil to rest within the transparent tube.

2. In a centrifugal machine for removing precipitated wax from hydrocarbon oils, the centrifugal machine being provided with a rundown line for discharging substantially wax free oil from the machine, the improvement which comprises a trough extending within the rundown line 25 for withdrawing at least a portion of the oil from the rundown line, a transparent tube communicating with the trough for visibly confining the oil withdrawn from the rundown line, means for returning said portion of oil to the rundown line, and means disposed intermediate 30 the transparent tube and said returning means for bringing said portion of oil to rest within the transparent tube.
